RADIO APPARATUS

Arthur T. Carney, Blairsville, Pa., assignor of
one-third to R. E. Miles, Jr., Wilkinsburg, Pa.

Application April 20, 1932, Serial No. 606,459

7 Claims. (Cl. 200—8)

This invention relates to switches which are especially adapted and constructed for use in connection with radio cabinets, and has for one of its objects the production of a simple and efficient switch which is particularly designated for use in connection with means for automatically and visibly designating the geographic location of the broadcasting station from which a radio program is being received.

10 Another object of this invention is the production of a simple and efficient electric switch for use in conjunction with radio turning dials the various portions of the switch being so constructed as to provide an efficient electrical contact for a turning dial.

With these and other objects in view, this invention consists in certain novel constructions, combinations, and arrangements of parts as will be hereinafter fully described and claimed.

20 In the drawing:

Figure 1 is a side elevation of the distributing dial of associated parts for controlling the operation of the electrical designating means;

Figure 2 is a section taken on line 2—2 of Figure 1;

Figure 3 is a longitudinal section through the distributor finger, certain parts being shown in section, the conducting band being also shown in transverse section;

30 Figure 4 is a section taken on line 4—4 of Figure 3;

Figure 5 is a fragmentary perspective view of a portion of the distributing dial showing the various contacts carried thereby;

35 By referring to the drawing it will be seen that 9 designates a tuning dial which may be operated in any suitable or desired manner as is common to the trade, whereby rotary movement may be imparted to the tuning dial shaft 10 as the tuning dial 9 is rotated to indicate the wave length of the station from which reception is being obtained.

40 This shaft 10 supports an insulated disc 11 upon which is secured at either side, a conducting disc plate 12 preferably formed of aluminum. Each plate 12 is provided with a projecting longitudinally slotted arm 13 upon which arm 13 is slidably and adjustably mounted the distributor finger 14.

45 The distributor finger 14 is securely fastened within the slotted arms by means of the securing screws 15 which pass through the slots 16 of the arms 13. The screws 15 may be secured to the distributor finger in any suitable or desired manner. The securing screws 15 also pass through the arc slot 17 formed in the side bands

18, which side bands are carried by the distributing dial 19. This distributing dial 19 is mounted upon the distributor base 20 formed of bakelite, or other non-conducting material, which base 20 is provided with an upwardly extending arc shaped distributing disc supporting plate 21, as shown in Figure 1, the respective ends of the distributing disc being anchored in any suitable or desired manner thereto.

50 The distributing disc 19 comprises a pair of spaced substantially semi-circular sections 19a and 19b, each being formed of insulating material and within which are molded suitable contact plates 22, the contact plates on the sections 19a and 19b being arranged in progressively spaced relation so as to cause only one contact plate to close a circuit with the distributor finger hereinafter more fully described. Each contact plate 22 may be provided with suitable means indicated by the numeral 23, projecting from the outer face thereof for the purpose of permitting an electrical conducting wire to be connected thereto. Electric conducting wires may be connected in any suitable or desired manner to these conducting plates without departing from the spirit of the invention in view of the fact that this electrical connection may be made in any suitable manner as is common to the trade.

55 The distributor finger 14 comprises a head 24 upon which is mounted a spring-pressed shoe 25, 85 this shoe carrying a plurality of studs 26 which fit in sockets 27 formed in the head 24, suitable coil springs 28 being mounted in the sockets 27 for the purpose of urging the shoe 25 outwardly and in contact with the inner face of the distributing 90 dial 19. An indicating finger 29 is carried by the outer face of the shoe 25 and travels upon the spaced sections 19a and 19b of the distributing dial, as shown clearly in Figure 3. The shoe 25 is also electrically connected by means of a wire 30 95 to a spring-pressed pin 31 mounted within a receptacle 32 and this spring-pressed pin 31 normally closes a contact with the conducting band 33, this conducting band being secured at one end as at 34, to the plate 21 and being yieldably supported upon the spring 35 carried by the pin 36, the pin 36 being supported upon the bracket 37 carried near the upper end of the plate 21. This contact band 33 partly encircles the disc 11 and comprises an open ended band, the ends of which 100 are supported, as shown in Figure 1, and as described specifically above. The band is mounted so as to pass between the arms 13 and arranged in spaced relation with respect to these arms. A buffer spring 38 is supported upon one end of the 110

distributor finger 14 and is interposed between one end of the finger 14 and the contact band 33, the buffer spring 38 preferably being mounted upon the distributor finger at an end opposite the spring-pressed contact pin 31, as shown in Figure 3. By means of the structure just described a very simple and efficient mechanism has been provided for properly closing the electrical circuits in order to carry out the purpose of the present invention.

As is shown in the drawing, the distributing dial is preferably constructed on the front side thereof of bakelite, hard rubber, or other non-conducting material which may, if desired, also constitute a part of the base, the base being capable of being anchored in an adjusted position within a suitable cabinet. The back or inner face of the distributing dial is also preferably constructed of non-conducting material and is preferably cast and machined with precision to allow for the proper positioning and alignment and insertion of the numerous contacting plates 22 which cooperate with the shoe 25 to complete an electrical circuit through the contact band 33. As shown in the drawing, these plates 22 are preferably beveled and in addition should be rigidly secured in place within the disc, the contact plates 22 being machined to extend flush with the inner face of the distributing dial to permit the shoe 25 to easily move thereover and properly form an electrical contact therewith.

The distributor finger 14 is also preferably formed of bakelite, hard rubber, or other non-conducting material, and is adapted to conform to the movement of the revolving disc 11, the finger 14 being held in proper position by the two supporting arms 13. The pin 31 and buffer spring 38 will assist in holding the distributor finger in proper position. By means of the contact band 33 it will be seen that the necessity of employing a multiplicity of wires to form a contact with the distributor finger will be eliminated, the use of which wires would complicate the construction and increase the possibility of breakage. Consequently, a substitute contact means in the nature of the band 33 has been provided. The purpose of this contact band 33 is to supply current for the full range of the distributor finger, as will be obvious.

In order to illustrate more clearly the method of using the present switch, I have illustrated a lamp 4 mounted upon a suitable support, the lamp 4 being adapted to indicate the position of a selected radio broadcasting station. Any number of these lamps may be used and mounted upon a suitable support as illustrated, to designate certain locations of various broadcasting stations, the purpose being to illuminate these lamps selectively at certain times to cause the lamps to burn while a certain designated radio station is broadcasting. As illustrated in Figure 1, the lamp 4 is electrically connected to a wire 40 which wire 40 is connected to one side of the line through a suitable transformer. The other side of the lamp 4 is connected by means of a selected wire 43 to one of the contact plates 22 which will register with the wave length indications appearing upon the tuning dial 9 thereby causing the light which is geographically located at a selected broadcasting station to be illuminated when the tuning dial 9 indicates the wave length of said station. The selected contact plate 22 is of course properly connected to the opposite side of the lamp 4 located at a point indicating the geographic location of the selected broadcasting station.

Having described the invention, what I claim as new is:—

1. A switch for use in connection with radio receiving apparatus comprising a supporting shaft, a distributor finger secured to and carried by said supporting shaft, supporting arms for said finger, a distributing dial, guiding means carried by said distributing dial for guiding said finger in its movement, a contact band, friction contact means carried by said distributing finger engaging said contact band for providing an electrical connection therebetween, and yieldable contact means carried by said distributor finger for yieldably contacting with said distributing dial. 80

85

90

2. A switch for use in connection with radio receiving apparatus comprising a shaft, a distributor finger secured to and carried by said shaft, supporting arms for said finger, a distributing dial, guiding means carried by said distributing dial for guiding said finger in its movement, a contact band, friction contact means carried by said distributing finger engaging said contact band for providing an electrical connection therebetween, a spring-pressed shoe extending transversely of said distributor finger and yieldably and frictionally engaging the inner face of said distributing dial, said distributing dial being provided with a plurality of selective contact means for contact with said shoe, whereby a circuit may be closed when said shoe is electrically and selectively brought into engagement with said contact means on said distributing dial. 100

105

110

3. A switch for use in connection with radio receiving apparatus comprising a shaft, a distributor finger secured to and carried by said shaft, supporting arms for said finger, a distributing dial, guiding means carried by said distributing dial for guiding said finger in its movement, a contact band, friction contact means carried by said distributing finger engaging said contact band for providing an electrical connection therebetween, a spring-pressed shoe extending transversely of said distributor finger and yieldably and frictionally engaging the inner face of said distributing dial, said distributing dial being provided with a plurality of selective contact means for contact with said shoe, whereby a circuit may be closed when said shoe is electrically and selectively brought into engagement with said contact means on said distributing dial. 115

125

130

4. A switch for use in connection with radio receiving apparatus comprising a shaft, a distributor finger secured to and carried by said shaft, supporting arms for said finger, a distributing dial, guiding means carried by said distributing dial for guiding said finger in its movement, a contact band, friction contact means carried by said distributing finger engaging said contact band for providing an electrical connection therebetween, a spring-pressed shoe extending transversely of said distributor finger and yieldably and frictionally engaging the inner face of said distributing dial, said distributing dial being provided with a plurality of selective contact means for contact with said shoe, whereby a circuit may be closed when said shoe is electrically and selectively brought into engagement with said contact means on said distributing dial, an indicating finger carried by said distributor finger and cooperating with said distributing dial to indicate the position of said distributor finger upon said dial. 135

140

145

150

to indicate the position of said distributor finger upon said dial, and spring buffer means interposed between said distributor finger and said contact band.

- 5 5. A circuit closing means of the class described comprising a distributing dial having a plurality of selected contact means formed thereon and flush with the inner face thereof, a distributor finger, said distributing dial being formed of a plurality of spaced sections, an indicating finger carried by said distributor finger and working between said spaced sections to indicate the position of said distributor finger with respect to said distributing dial, contact means carried by said distributor finger for contacting with the inner face of said distributing dial, and means for setting up an electrical circuit between said distributing dial and said distributor finger.
6. A circuit closing means of the class described comprising a distributing dial having a plurality of selected contact means formed thereon and flush with the inner face thereof, a distributor finger, said distributing dial being formed of a plurality of spaced sections, an indicating finger carried by said distributor finger and working between said spaced sections to indicate the position

of said distributor finger with respect to said distributing dial, contact means carried by said distributor finger for contacting with the inner face of said distributing dial, a contact band anchored at one end, means for yieldably supporting the other end of said contact band, yieldable means for setting up a frictional contact between said distributor finger and said contact band, and means for completing an electric circuit between said distributing dial and said contact band.

7. A switch for use in connection with radio receiving apparatus comprising a supporting shaft, a distributing dial, a contact band mounted concentrically within and spaced from said distributing dial, means for yieldably supporting said contact band, a contact member carried by said shaft and movable over the face of said distributing dial and yieldable frictional contact means carried by said contact member interposed between said distributing dial and said contact band for maintaining a constant electrical contact between the contact band and said distributing dial as said contact member is moved between the contact band and the distributing dial in either a clockwise or counter-clockwise direction.
